UNITED STATES PATENT OFFICE.

JOHN BRANDT, OF NEW YORK, N. Y., ASSIGNOR TO AUTOSALES CORPORATION, OF LONG ISLAND CITY, NEW YORK, A CORPORATION OF NEW YORK.

VENDING MACHINE.

Application filed November 21, 1922. Serial No. 602,410.

To all whom it may concern:

Be it known that I, JOHN BRANDT, a citizen of the United States, and resident of New York, county of Bronx, and State of New York, have invented certain new and useful Improvements in Vending Machines, of which the following is a specification.

My invention relates to the art of slot machines adapted to deliver a piece of goods in exchange for a previously deposited coin. The main object of my invention is to provide certain improvements in machines of the type shown in Grover Patent No. 1,385,822, dated July 26, 1921, which embodies a plurality of unit delivery mechanisms capable of being removed and inserted independently of each other.

It was found by experience that in the Grover machine of the patent just mentioned, where the frameworks of the individual delivery units are supported at the rear on a cross-piece fixed in the cabinet of the machine, it was necessary to adjust each delivery unit separately. This was due to the fact that the top edge of the cross-piece, on which the rear ends of the delivery units rested, would not always be at the correct height and would naturally vary in different machines. On this account it was sometimes found that a delivery unit which fitted in one machine would not fit in another machine, or even in a different position in the same machine, without the necessity of raising or lowering the engaging top of the cross-piece.

Now, in the proper maintenance of these machines, it is necessary that the delivery units be absolutely interchangeable, not only within the same machine, but indiscriminately in all machines of the same type. It is the purpose of my present invention to accomplish this very desirable object by providing a new and improved supporting framework for the delivery units, so that any unit is sure to fit in any place in the same machine and in any other machine of like style. This makes it possible for an agent in charge of a number of machines to keep on hand a stock of extra delivery units, which can be used to replace any delivery unit that has been put out of commission.

A preferred form of my invention is illustrated in the accompanying drawings, in which

Fig. 1 shows a perspective view of a vend-

ing machine containing the features of my invention, the upper portion of the outer casing being broken away;

Fig. 2 is a vertical cross-section approximately on the broken line 2—2 of Fig. 1, looking in the direction of the arrows;

Fig. 3 is a detached perspective view of my new framework for supporting the delivery units, one of which is shown in place;

Fig. 4 is a plan view of a portion of my new framework;

Fig. 5 is a side view of the framework shown in Figs. 3 and 4;

Fig. 6 is a fragmentary view in section, approximately on line 6—6 of Fig. 4;

Fig. 7 is a fragmentary view in cross-section, approximately on line 7—7 of Fig. 5;

Fig. 8 is a fragmentary view in cross-section approximately on line 8—8 of Fig. 5, showing how the framework fits in between the side walls of the cabinet of the machine;

Fig. 9 is a cross-section approximately on line 9—9 of Fig. 3, showing how the delivery units are supported between the flanges of the framework; and

Fig. 10 is a bottom plan view of a portion of the framework, showing how the longitudinal strips thereof are secured at their lower edge to the cross-pieces.

The vending machine illustrated in the drawings has an outer casing or cabinet, indicated as a whole by C, of any suitable material and construction. Within the cabinet are mounted the usual magazines M containing the goods to be sold. In the present instance, there are four magazines, but the number of magazines is immaterial. The upper chamber of the cabinet which contains the magazines is closed by a front panel 1, which is readily removable and is locked in closed position. In Fig. 2, I have shown the front panel 1 provided with lugs 2 arranged to engage fixed pins 3 carried by the sides of the casing. This is a common construction and I have shown it merely by way of convenience.

A transverse panel 4 is rigidly mounted between the sides of the cabinet in the lower portion thereof, as shown in Fig. 2. The space 5 between the lower edge of panel 4 and the base of the machine constitutes the delivery opening for the goods. Back of the panel 4 is fixed a transverse cross-piece 6, which is held in position in any convenient way. The space 7 between the back of cross-

2
 piece 6 and the curved guide-plate 8 is the discharge passage through which the ejected goods travel to the delivery opening 5. The rear wall of panel 4 carries a plate 9 having a flange 10. A door 11 is hinged at 12 along the lower edge of cross-piece 6 and bears at its front edge against the flange 10. Panel 4, door 11 and cross-piece 6 thus form a closed chamber which 10 may be called the cash box of the machine, because the deposited coins drop into that space when they are released from the coin mechanism. The door 11 is held in closed position by a pair of side wires 13, which 15 hook over the respective side lugs 3, as shown in Fig. 2. By simply snapping the wires 13 out of engagement with lugs 3, the operator releases door 11 and the coins drop into the delivery opening 5, from which they 20 are removed. It should be understood, of course, that the cash box cannot be opened as long as the front panel 1 is in position on the casing, because the metal plate 14 secured to the lower edge of panel 1 closes 25 all access to the wires 13.

As seen in Fig. 1, the machine carries four delivery units, indicated each as a whole by D. Each unit is in alignment with a magazine M. These units are of substantially identical construction and it will not be necessary to describe them in detail, for the reason that they do not in and of themselves form part of my invention. These delivery units are practically the same in construction as the delivery units shown 30 in the aforementioned Grover Patent No. 1,385,822, and reference thereto may be had for the structural details of these units. It is enough to say that each delivery unit has a top plate 15 and a plunger 16. When the units are assembled in the machine, the top plates 15 form in effect a single plate which forms part of the outer front wall of the cabinet, as may be seen from Fig. 1. When 40 the plunger 16 is pushed inwardly, after the deposition of a proper coin in the corresponding coin-slot 17, a piece of goods is pushed out of the bottom of the associated magazine and falls to the mouth of delivery opening 5, as described in detail in said Grover Patent No. 1,385,822.

The delivery units D are supported in a frame-work indicated as a whole by F and best shown in Fig. 3. The framework F is preferably constructed of sheet metal, such as brass, and has a pair of side rails 18 and 19. For the sake of clearness I will call the rear section of each side rail an extension α , which is slightly offset with respect 55 to the front section. This is clear from Figs. 3, 4, 5 and 7. The side rails 18 and 19 are connected at the front by cross-bar 20 and at the rear by a channel bar 21. I might also provide an intermediate connecting bar 60 22. The side rails 18 and 19 have each an

inwardly extending flange 23, to which the cross-bars 20 and 22 are secured by rivets 24 or otherwise. This is best shown in Figs. 4, 7 and 8. The channel bar 21 is secured between the side rails by rivets 25, as shown 70 in Figs. 3, 4 and 5.

The side rails 18 and 19 are formed with an offset portion 26 terminating in a top flange 27. The purpose of the offset portion 26 is to engage a correspondingly shaped 75 slot or groove 28 formed in the adjacent side of the cabinet, as best shown in Fig. 8. In this way, the framework as a whole is readily slidable into and out of the cabinet. Between the side rails 18 and 19 of the 80 framework are secured pairs of strips 29 substantially parallel with the side rails and properly spaced as shown in Fig. 3. Each pair of strips 29 is rigidly secured together and is in effect a single strip with oppositely 85 extending flanges 30. The strips 29 pass through slots a in the channel bar 21 and provided with lugs b arranged to extend through slots in the rear flange of the channel bar, as shown in Fig. 6. By upsetting the lugs b in the manner of rivets, the strips 29 are rigidly secured in the framework. The strips 29 may also be provided with lugs c at their lower edges in position to pass 90 through holes in the cross-bars 20 and 22, and adapted to be upset similar to the lugs b . This is shown in Fig. 10.

It will be seen from Fig. 3, that the flanges 30 of strips 29, in conjunction with the flanges 27 of the side rails 18 and 19, provide pairs of parallel flanges so spaced as to support a delivery unit D between each pair of flanges. In Fig. 3, one of the delivery units is shown in position on the framework. Fig. 9 shows how each framework is 100 in slidable engagement with the associated pair of flanges. Each delivery unit has a bottom plate 31, formed with a groove 32 adapted to receive and interlock with the corresponding flange 30 of the framework. 105 In this way the delivery units are easily slid into position on the framework and as readily removed therefrom. The two delivery units next to the sides of the casing are supported between the flange 27 of the 110 associated side rail and the flange 30 of the next supporting strip 29.

Attention is called to the fact that the delivery units are supported entirely on the framework F. For this purpose, the side 115 rails 18 and 19 and the flanged strips 29 are of such length that the rear side plates 33 of each delivery unit rest on or are supported by the transverse channel bar 21, as shown in Figs. 2 and 3. So it is clear that 120 the delivery units are interchangeable, not only on the same framework, but on any other framework of like construction. As seen in Fig. 2, each goods magazine M is supported directly on the rear plates 33 of 125 130

the associated delivery unit. This makes it indispensable, owing to the weight of the magazine, that the rear plates 33 are always firmly supported, as is done in my new 5 framework.

When the framework F is slid rearwardly into the cabinet of the machine, the channel bar 21 rests on the top edge 34 of cross-piece 6, as shown in Fig. 2. In order to secure 10 the framework rigidly in position, I provide the channel bar with a forwardly and downwardly extending apron 35, which has holes 36 to receive screws 37, or other fastening devices. When once the framework F is 15 fixed in position in a cabinet, it is ready to receive interchangeably any one or more of the delivery units D, since these are supported entirely on the framework. It is in this important feature that the framework 20 of my invention differs from the framework in the Grover patent referred to. By thus eliminating the necessity of individually adjusting the delivery units, I secure an automatic fitting of all units when once the 25 framework is in position in a machine.

It is a common experience that delivery mechanisms of vending machines get out of order, either through hard usage or through unlawful attempts to work the machine 30 without coins, so that delivery mechanisms have to be frequently repaired and replaced. Usually these repairs cannot be made by the agent in charge of the machines in a certain locality, and so it has been necessary 35 to ship the machines back to the factory. This, of course, means a loss of revenue to the owner or operator of the machine. In the machines embodying my invention, when any particular delivery unit gets out of order, 40 all the agent has to do is to take it out and slip in its place a new unit, of which he always has a stock on hand. The old unit is then shipped to the factory for repair. In this way a machine can be kept in good 45 working order all the time.

I may provide the machine with a guard-plate to prevent attempted insertions of sharp instruments into the thin cracks between adjacent delivery units. In Figs. 1 50 and 2, I have shown a guard-plate 38, having a hook-shaped upper edge 39 adapted to hook over the front edges of the unit delivery mechanisms. The guard-plate 38 is held in position by any suitable means. In 55 the drawings I have shown a plate 40 set into the front wall of panel 4 and secured thereto by screws 41. The guard-plate 38 is fastened to the inner plate 40 by special screws 42. By special screws I mean such 60 as cannot be manipulated by the ordinary screw-driver, but require a special tool which a person would not ordinarily have on hand. For instance, in Fig. 1, I have shown the screws 42 provided with heads having each a pair of holes 43 adapted to re-

ceive a pair of correspondingly arranged pins on a screw-driver.

The guard-plate 38 locks the delivery units D in the casing, but I may employ additional locking means by providing each 70 unit with a lug 44 (see Figs. 2 and 3) arranged to engage the metal plate 14 when the panel 1 is in position.

I claim as my invention:

1. In a vending machine, an outer casing, a plurality of upright magazines mounted therein, a cross-piece in said casing below said magazines, a main framework mounted between the sides of said casing and having a rear extension supported on said cross-piece, said framework being provided with pairs of flanges running substantially parallel with the sides of the casing, a unitary framework supported between each pair of said flanges substantially in alignment with one of said magazines, each unitary framework having a pair of rearwardly extending side plates adapted to rest on said rear extension, whereby said unitary frameworks are directly supported entirely on said main 80 framework side by side independently of each other, so that each unitary framework is removable from and insertible into said main framework as a single unit and is interchangeable with any other unitary framework in the machine, and delivery mechanism carried by each unitary framework, each unitary framework and its delivery mechanism constituting a single independent 85 unit. 90

2. In a vending machine, an outer casing, a plurality of upright magazines mounted therein, a cross-piece in said casing below said magazines, a main framework mounted between the sides of said casing and having a rear extension supported on said cross-piece, said framework being provided with pairs of flanges running substantially parallel with the sides of the casing, a unitary framework supported between each pair of said flanges substantially in alignment with one of said magazines and carrying a delivery mechanism, each unitary framework having a pair of rearwardly extending side plates adapted to rest on said rear extension, whereby said unitary frameworks are directly supported entirely on said main framework side by side independently of each other, and a guard plate secured over the front edges of said unitary 105 frameworks. 110

3. In a vending machine, an outer casing, a plurality of upright magazines mounted therein, a cross-piece in said casing below said magazines, a main framework mounted between the sides of said casing and having a rear extension supported on said cross-piece, said framework being provided with pairs of flanges running substantially parallel with the sides of the casing, a unitary 115 framework having a pair of rearwardly extending side plates adapted to rest on said rear extension, whereby said unitary frameworks are directly supported entirely on said main framework side by side independently of each other, and a guard plate secured over the front edges of said unitary 120 frameworks. 125

65

framework supported between each pair of said flanges substantially in alignment with one of said magazines and carrying a delivery mechanism, each unitary framework 5 having a pair of rearwardly extending side plates adapted to rest on said rear extension, whereby said unitary frameworks are directly supported entirely on said main framework side by side independently of 10 each other, a guard plate having a hook-shaped upper edge adapted to hook over the front edges of said unitary frameworks, and means for securing said guard plate in position on the casing.

15. 4. In a vending machine, an outer casing, a plurality of upright magazines mounted therein, a cross-piece in said casing below said magazines, a main framework mounted between the sides of said casing and having 20 a rear extension supported on said cross-piece, a plurality of unitary frameworks slidably mounted on said main framework side by side independently of each other, each unitary framework having a portion 25 resting on said rear extension of the main framework, whereby each unitary framework is directly supported entirely on said main framework, and a delivery mechanism carried by each unitary framework.
30. 5. In a vending machine, an outer casing, a plurality of upright magazines mounted therein, a cross-piece in said casing below said magazines, a main framework mounted between the sides of said casing and having 35 an extension supported on said cross-piece, a plurality of unitary frameworks slidably mounted on said main framework side by side independently of each other, each unitary framework having a portion resting on 40 said rear extension of the main framework, whereby each unitary framework is directly supported entirely on said main framework, and a guard plate secured over the front edges of said unitary frameworks.
45. 6. In a vending machine, an outer casing, a plurality of upright magazines mounted therein, a cross-piece in said casing below said magazines, a main framework mounted

between the sides of said casing and having a rear extension supported on said cross-piece, a plurality of unitary frameworks slidably mounted on said main framework side by side independently of each other, each unitary framework having a portion resting on said rear extension of the main framework, whereby each unitary framework is directly supported entirely on said main framework, a delivery mechanism carried by each unitary framework, a guard plate having a hook-shaped upper edge 60 adapted to hook over the front edges of said unitary frameworks, and means for securing said guard plate in position on the casing.

7. As a new article of manufacture for supporting a plurality of delivery mechanisms in vending machines, a framework made of sheet metal and comprising a pair of side rails bent outwardly to form engaging flanges, cross-pieces connecting said side rails, an extension formed on each side rail as a rearward continuation thereof, a transverse channel bar secured to the ends of said extensions, and a plurality of parallel longitudinal strips secured at their lower edge to said cross-pieces and at their rear edge to said channel bar, said strips being so constructed and arranged as to form pairs of spaced supporting flanges.

8. As a new article of manufacture for supporting a plurality of delivery mechanisms in vending machines, a framework made of sheet metal and comprising a pair of side rails bent outwardly to form engaging flanges, cross-pieces connecting said side rails, an extension formed on each side rail as a rearward continuation thereof, a transverse channel bar secured to the ends of said extensions and having a downwardly projecting apron, and a plurality of parallel longitudinal strips secured at their lower edge to said cross-pieces and at their rear edge to said channel bar, said strips being so constructed and arranged as to form pairs of spaced supporting flanges.

JOHN BRANDT.
